PAPER FEEDING MECHANISM FOR
ACCOUNTING MACHINESArthur Leon Booten, Brussels, Belgium, assignor
to Underwood Corporation, New York, N. Y., a
corporation of DelawareApplication June 5, 1947, Serial No. 752,589
In Belgium July 14, 1943Section 1, Public Law 690, August 8, 1946
Patent expires July 14, 1963

5 Claims. (Cl. 197—133)

1

This invention relates to accounting machines, and more particularly to a continuous form feeding apparatus therefor.

Business establishments such as public utilities companies frequently print their consumers' bills on a continuous form having tear lines between each bill to facilitate their detachment, one from the other, for distribution to the respective consumers. Generally, space is provided on the bills to accommodate several lines of the data to be printed, the number of lines to be used on a particular consumer's bill varying in accordance with the character of the particular utility company's commodity and also in accordance with the consumption of that commodity by the consumer.

In printing the data on these bills, it is ordinarily desirable to have a carbon copy of the printing on a journal sheet, and to have the journal sheet and the continuous bill form advance together for line spacing.

It is further desirable to have the first line of the next succeeding bill advanced to printing position automatically.

It is an object of the present invention, therefore, to provide a continuous form feed mechanism that will automatically advance the forms to present the first line of the next succeeding form at the printing position, irrespective of the number of lines printed on the preceding form.

Another object of the invention is to provide a paper feeding apparatus of this character which provides simultaneous uniform line spacing of a continuous bill form and a carbon form about a single platen, and which also permits automatic non-uniform advancement of the forms.

A further object of the invention is to provide a simple and inexpensive magazine for the continuous forms that will cooperate with the carriage and the paper feeding apparatus in supplying and receiving the bill forms, to and from the carriage.

With these and incidental objects in view, the invention consists in certain novel features of construction and combinations of parts, the essential elements of which are set forth in appended claims, and a preferred embodiment of which is hereinafter described with reference to the drawings which accompany and form part of the specification.

In the drawings:

Figure 1 is a perspective view of the entire machine embodying the invention,

Figure 2 is a perspective view of the carriage taken from the left front corner,

2

Figure 3 is a right side elevation of the line spacing mechanism,

Figure 4 is a detail sectional view taken on the line 4—4 of Figure 3,

Figure 5 is a right side sectional elevation of the carriage showing the path of the forms in the carriage,

Figure 6 is a detail left side elevation of the friction clutch used in conjunction with mechanism for advancing the continuous forms,

Figure 7 is a detail sectional view taken on the line 7—7 of Figure 6,

Figure 8 is a detail left side elevation taken on the line 8—8 of Figure 7,

Figure 9 is a fragmental top plan view of certain of the parts used for advancing the continuous forms,

Figure 10 is a rear elevation thereof,

Figure 11 is a detail perspective of a hook shown in Figures 9 and 10, and

Figures 12, 13 and 14 are diagrams illustrating the relative advance of the continuous forms and the carbon journal sheet, and illustrating the printing of the items thereon.

25 The present mechanism is shown applied to a key set, motor actuated accounting machine having a traveling paper carriage equipped with suitable control lugs to control various operations of the machine as the carriage tabulates from column to column. The present mechanism is shown as applied to a machine of the type fully disclosed in U. S. Patent No. 2,194,270, of Oscar J. Sundstrand, and U. S. Patent No. 2,226,960 of Walter A. Anderson.

30 35 INDEX OF TOPICS

1. The machine sections and general operating mechanisms.
2. Line space mechanism for journal sheet.
3. Supporting and line spacing mechanism for continuous bill forms.
4. Mechanism for differentially advancing the continuous forms.
5. Operation.

45 1. *The machine sections and general operating mechanisms*

Referring to Figure 1, the machine generally indicated at 1, is mounted upon a stand 2. A magazine 4, from and into which are fed the continuous forms 5, is pivoted at 3 on stand 2. A laterally movable paper carriage indicated generally at 6 is mounted on a rail 7 on anti-friction rollers 8 (Figure 3). It is moved from right to left (Figure 2) in its working stroke,

3

and is stopped in its several columnar positions by suitable tabulating mechanism, such as that described in the above mentioned patents. A suitable carriage return mechanism, which may also be similar to that described in the above mentioned patents, returns the carriage to its right hand position after it has completed its working stroke. While the carriage rests in each of the several columnar positions, the machine is operated to perform the necessary accounting functions, and to print the proper entries upon the continuous forms 5.

As before stated, the supporting magazine 4 is pivoted at its lower end at 3, and is connected by a suitable universal connection to a rearward extension of the carriage, so that as the carriage moves back and forth, magazine 4 rocks on pivot 3. Magazine 4 has a partition 11 (Figure 1) to the left of which are placed the supply of continuous forms, and to the right of which are stacked the completed forms after they have passed through the carriage.

To perform the printing and computing operations, the machine is provided with a main actuating shaft (not shown) which is oscillated first counter-clockwise and then clockwise to its home position, as disclosed in the above mentioned patents. Through suitable connections between this actuating shaft and a link 12 (Figure 3), oscillation of the shaft raises and lowers the link during each machine cycle.

2. *Line space mechanism for journal sheet*

The conventional line space mechanism similar to that disclosed in the afore-mentioned patents is provided on this machine for advancing the journal sheet and its accompanying carbon sheet. This mechanism includes a bell crank 13 (Figure 3) pivoted at 14 and connected at 15 to the upper end of link 12. The movement imparted to link 12 first oscillates bell crank 13 clockwise to the position shown in dotted lines, and then counter-clockwise to its normal position. A roller 16 on the upper arm of bell crank 13 receives a corresponding movement.

A cradle comprised of rods 17 and 18, and end plates 19 and 20 (see also Figure 2), is pivoted in the carriage frame on rod 17, and is tensioned clockwise as viewed in Figure 3 by a spring 22 fastened to the forward end of plate 19. Clockwise movement of the cradle is limited by roller 16. A line spacing finger 23 is pivoted at 24 to plate 19 and has its forward end tensioned upwardly by a spring 25 attached to the rear end of the finger and to a lever 26 also pivoted on plate 19 at 27. For the purpose of the present disclosure, lever 26 may be considered only as an anchor for spring 25. Plate 19 has a flange 28 overlying the finger 23 to limit the amount of movement of the finger about pivot 24 under the tension of spring 25. A toothed ratchet wheel 30 is secured to the right end of a shaft 31 upon which is mounted a platen 32, the shaft being journaled at its opposite ends in the carriage side walls 33 and 34 (Figure 2).

By the above described parts, the initial clockwise oscillation of bell crank 13 (Figure 3) moves roller 16 to the rear, allowing spring 22 to rock the cradle to the rear and thereby move also the forward pointed end of finger 23 to the rear. During this movement, finger 23 rises under the tension of spring 25 until it strikes wheel 30, and then moves rearwardly past one tooth. As it leaves this tooth, it rises until it strikes a pin

4

35 of an adjustable line space regulating arm 36 pivoted at 37 on the right carriage side wall 34. This holds finger 23 away from wheel 30 for the remainder of the clockwise oscillation of the bell crank. During the ensuing counter-clockwise movement of bell crank 13, finger 23 engages the tooth it just passed, and rotates wheel 30 a distance sufficient to impart a single line space to the paper. When the line space movement is just completed, flange 28 strikes the upper edge of finger 23, moving it out of engagement with wheel 30.

Referring to Figures 2 and 5, the journal sheet 38 together with a carbon 41 is inserted downwardly over a paper table 42 extending between the carriage side walls, then under the platen 32, between pressure rolls 43 and the platen. From there it passes upwardly in front of the platen and then rearwardly under a bail 44 pivoted at 45 in the carriage side walls. Rotation of the ratchet wheel 30, as above described, rotates the platen, which, through the cooperation of pressure rolls 43, advances the journal and carbon sheets.

25 3. *Supporting and line spacing mechanism for continuous bill forms*

A supply of continuous bill forms is supported in the magazine 4 (Figure 1) to the left of partition 11. From there they extend upwardly over a guide rod 46 (Figure 5), downwardly behind paper table 42, under pressure rolls 43, upwardly past platen 32, over a feed roll 47, rearwardly over rods 48 (Figure 2), downwardly between 35 parallel edge guides 51 (Figure 1), and into magazine 4 to the right of partition 11.

For line spacing the continuous bill forms, the following structure is provided. A pressure roll 52 is journaled at its opposite ends in arms 53 (Figure 2) pivoted at 54 to upwardly extending brackets 55 secured on the carriage side walls. Roll 52 is tensioned toward feed roll 47 by springs 56, so that when the feed roll 47 is rotated, the continuous forms 5 are advanced.

45 A means is provided to move pressure roll 52 away from feed roll 47 to facilitate introduction of the continuous forms. This means includes a bail 57 having side arms 58 pivoted at 61. Arms 58 each have rearwardly extending projections such as 62 (Figure 5). The shaft which supports pressure roll 52 rests on the upper edges of these projections 62 under the tension of springs 56. Upon swinging bail 57 counter-clockwise (Figure 5) about pivot 61, projections 62 cam the feed roll shaft upwardly about pivot 54, against the tension of springs 56, until the shaft rests in recesses 63 in the projections 62. This holds pressure roll 52 out of feeding relation with feed roll 47 and permits sufficient clearance for the easy introduction of the leading end of a new strip of continuous forms. A clockwise rocking of bail 57 by the operator will then allow springs 56 to move pressure roll 52 into feeding relation with the paper.

65 Feed roll 47 is line spaced together with platen 32 through the following parts. A vertically disposed rod 64 (Figure 3) is pivoted at its lower end in an arm of a bracket 65 fixed on the outer end of rods 17 and 18 of the line space cradle. The upper end of rod 64 passes through an opening in a stud 66 fixed on an arm 67 of a plate 68 (see also Figure 4) of a friction clutch generally indicated at 71. A spring 72 normally tensions arm 67 and plate 68 counter-clockwise. A spring 73, encircling rod 64 between stud 66 and nuts

15 threaded on the upper end of the rod, holds plate 68 in the position shown in Figure 3 against the tension of spring 72 when bell crank 13 is in its normal position shown in Figure 3. Plate 68 is connected by screws 76 (Figure 4) to a clutch disk 71 mounted on a bushing 78 secured in right hand bracket 55. Bushing 78 also acts as a support for a shaft 81 that supports feed roll 47.

A series of balls 82 rest in suitable recesses in disk 71, and each is spring urged into contact with the inner periphery of a cup 83, the hub 84 of which is secured to the outer end of shaft 81. When the line space cradle swings bracket 65 clockwise, rod 64 is raised, and as the cradle swings the bracket counter-clockwise, rod 64 is lowered. As rod 64 rises, plate 68 and disk 71 are rotated counter-clockwise until the upper end of arm 67 strikes a stop screw 85. During this movement balls 82 are urged toward the wide end of the recesses, so that no movement is imparted to cup 83 and feed roll 47. However, when rod 64 is lowered, disk 71 is rotated clockwise, causing balls 82 to move toward the narrow end of their recesses, their respective springs assisting them in this movement. This causes the balls to act as a wedge between the disk 71 and the inner periphery of cup 83, to permit rotation of the disk to rotate the cup and feed roll 47 a distance sufficient to advance the bill form one line space. The advancing movement is limited by a pin 86 that lies in the path of arm 67.

Stop screw 85 may be adjusted to vary the extent of movement imparted to the bill form. By such an adjustment, the line spacing movements of the bill form may be made equal to or different from the line spacing movements of the journal sheet, as desired.

By the above described mechanism, line spacing movements of the journal sheet are accompanied by line spacing movements of the bill form upwardly past the front of the platen.

4. Mechanism for differentially advancing the continuous form

As before stated, it is desirable that following a printing of the last line upon one of the continuous forms 5, the first line of the next succeeding form be brought into printing position, irrespective of the number of lines printed upon the preceding form. This is accomplished in the present structure during the return stroke of the carriage, i. e., as the carriage moves from left to right, and is performed by the following parts.

A finger 87 (Figures 6 and 7) is secured on the left end of feed roll shaft 81 that extends through a bushing 88 mounted in the left bracket 55. Finger 87 lies in front of a pin 91 fixed in a disk 92 of a clutch generally indicated at 93. This clutch is similar to the clutch 71, except that the ball retaining disk is the driven element in this clutch, whereas it is the driving element in clutch 71. Disk 92 is freely rotatable upon the reduced left end of bushing 88, and carries a series of balls 94 in suitable recesses therein. The balls engage the inner periphery of a cup 95 having a hub 96 rotatably mounted on bushing 88. A cup 97 is secured to the outer end of the cup to completely encase the parts. A spring 98 (see also Figure 8) encircles the hub 96, and has one of its ends connected thereto at 101. The opposite end of the spring is connected at 102 to a plate 103. The spring and plate 103 lie within a housing 105, the plate and housing being secured to the left bracket 55 by screws 104.

A drum 106 encircles housing 105, and is se-

cured to cup 95 by screws 107, for rotation with the cup. Spring 98 normally tends to rotate cup 95 and drum 106 clockwise (Figures 2 and 6) about bushing 88, to cause a tape 108 (Figure 7) connected to the drum at 111, to be wound thereon. Tape 108 passes from the drum (Figure 2) over pulleys 112 and 113 supported on the carriage, and is connected at 115 to a block 116 secured on a horizontally disposed rod 118 (see also Figures 9 and 10). Rod 118 is provided with an eye 121 arranged to engage a hook 122 pivoted at 123 (Figures 9, 10 and 11) to the under side of an extension 124 fixed on the left end of carriage rail (Figure 2). The upper end of the hook extends through an aperture 125 in plate 124 and is normally held in effective position by a spring 126.

The operation of the above parts is as follows. When, during the working stroke of the carriage, it reaches the last position to the left (the one shown in Figure 2), eye 121 engages hook 122. At this time, the carriage return mechanism becomes operative, and moves the carriage to its right hand position. Since eye 121 is at this time held stationary by hook 122, the return movement of the carriage unwinds tape 108 from drum 106, against the tension of spring 98. Unwinding of the tape causes drum 106 to rotate cup 95 counter-clockwise (Figure 6), and since balls 94 become effective when it is rotated in this direction, disk 92 is rotated therewith, causing pin 91 of the disk to make one complete revolution. During this revolution, the pin picks up finger 87 and rotates feed roll 47 counter-clockwise a sufficient extent to bring the first line of the next form 5 into printing position.

This movement of feed roll 47 by the return movement of the carriage is always just sufficient to bring the first line of the next form into printing position, irrespective of the distance the form was previously advanced by the line spacing movements of rod 64. This is because finger 87 moves ahead of pin 91 an amount corresponding to the number of line space operations given by rod 64, so that the amount of movement imparted to the finger by the driven disk 92 is only the difference between the amount given by the rod 64, and the amount necessary to advance one bill form its entire length.

As the carriage completes its return movement, a screw 127 (Figures 2, 9 and 10) secured in the left carriage side plate 33 strikes a block 128 fixed on a rod 131 suitably guided on carriage rail 7. The right end of rod 131 (Figures 9 and 10) passes downwardly through a slot 130 in plate 124, and is pivoted at 132 to a lever 133. The opposite end of lever 133 is pivoted at 134 to the under side of extension 124. A spring 135 normally tensions lever 133 and rod 131 toward the right as viewed in Figures 9, 10 and 11, but upon screw 127 striking block 128, lever 133 is pulled toward the left, causing a cam surface 133a (Figure 11) thereon to cam hook 122 downwardly out of engagement with eye 121, to allow spring 98 to rewind tape 108 upon drum 106. During this rewinding action, the driving cup 95 slips idly over the balls, imparting no rotation to feed roll 47.

When the carriage starts its next working stroke, screw 127 moves away from block 128, allowing springs 135 and 126 to restore lever 133 and hook 122 to their normal positions shown in Figures 9, 10 and 11.

The inner end of rod 118 extends through carriage side wall 33 and carries a piston 136 sliding within a cylinder 137, suitably mounted by clamps

such as 138 on carriage rail 7. The left end of cylinder 137 has a needle valve 141 that controls passage of air from the cylinder. This construction provides a cushion for the rewinding action of spring 98. The rewinding action is stopped by block 116 striking the forked end of a bracket 114 secured to the carriage side wall 33.

Block 128 may be adjusted along rod 131 to advance or retard the disconnection of hook 122 from rod 118. This will vary the amount of feed imparted to the bill forms by the feeding mechanism operated by the carriage return mechanism, to exactly suit the length of the forms.

When spring 98 rewinds tape 108 on drum 106, the accompanying rotation of cup 95 has a tendency to rotate disk 92 clockwise, due to the tension of the small springs associated with the balls in the disk. This, however, is of no importance, since the movement is very slight, and will be substantially the same in every operation.

5. Operation

Let it be assumed that the bill forms 5, the carbon 41 and journal sheet 33 have been threaded in the carriage as described above. Referring now to Figure 12 (the journal sheet 33 is shown off to one side for the purpose of illustration only), after the printing in the left column of bill No. 73, the platen is moved to the left to print in the right hand column of the bill. At the end of this printing operation the platen is line spaced by the mechanism illustrated in Figure 3, under the control of the carriage, in the manner described in Patent No. 2,194,270. This line spacing operation advances finger 87 from pin 91 one step, as shown in Figure 12.

At the end of this cycle, the carriage tabulates to the left a short distance, in the manner described in the above mentioned patent, engaging the carriage return mechanism, and at the same time engaging eye 121 (Figure 9) with hook 122. The ensuing return movement of the carriage to the right causes tape 108 to be unwound from drum 106, and thereby rotates disk 92 counter-clockwise a fixed amount, which, in the present instance, has been described as one revolution. During this rotation of disk 92, pin 91 picks up finger 87, and from that point on it rotates the feed roll 47 to advance the bill forms 5. As bill No. 74 comes to the proper position for printing, hook 122 is disengaged from eye 121, arresting the feeding of the bill and allowing spring 98 to rewind tape 108, disk 92 remaining stationary during this reverse rotation of drum 106.

Referring to Figure 13, to print the first item in the left column of bill No. 74, the operator presses a special key which will prevent the machine from tabulating to the right hand column at the end of this operation, and which will also cause the line spacing mechanism of Figure 3 to operate. This control is designated the "Non-Tab Key" in the above mentioned patent.

In printing the second item in this column the special key is not operated, allowing the carriage to tabulate to the left and print in the right hand column, as in bill No. 73. At the end of this printing operation the line spacing mechanism is again operated, as described in connection with bill No. 73, and the carriage again moves the short distance to the left, engaging the carriage return mechanism and engaging eye 121 with hook 122. This time, however, since the line spacing mechanism of Figure 3 has operated twice, instead of once as in connection with bill No. 73, finger 87 has moved two steps away from pin 91. Therefore, upon the subsequent rota-

tion of disk 92, pin 91 picks up finger 87 at a later time in the operation, resulting in less movement of feed roll 47. The difference between the amount of movements of the feed roll 47 for bills No. 73 and No. 74 compensates for the additional line space movement given to bill No. 74.

In Figure 14, bill No. 75 shows a similar multiple line printing, three lines in this instance being shown. In connection with Figure 14, it will be noted that finger 87 is advanced a third step away from pin 91 due to three line space movements being given by the line spacing mechanism of Figure 3 during the printing on this bill.

The printing in the left column on the journal sheet appears on successive line spaces since the journal sheet is not advanced by rotation of roll 47.

If bill forms of greater or less length are to be used, the feeding movement of feed roll 47 would be changed accordingly. For instance, if the bill forms to be used are longer than the ones illustrated, block 128 (Figure 9) would be moved to the left to allow the return movement of the carriage to unwind more tape from drum 106 and thereby rotate roll 47 farther before screw 127 on the carriage frame strikes block 128 to release eye 121. This would cause the return movement of the carriage to always rotate disk 92 more than the one revolution described above. This change would of course be accompanied by corresponding change in the position of the well known carriage return dogs shown in Patent No. 2,194,270.

While the form of mechanism herein shown and described is admirably adapted to fulfill the objects primarily stated, it is to be understood that it is not intended to confine the invention to the one form of embodiment herein described, for it is susceptible of embodiment in various forms all coming within the scope of the claims which follow.

What is claimed is:

1. In a machine of the class described, a traveling paper-supporting carriage movable oppositely through working and return strokes on a frame, a mechanism on the carriage for advancing continuous forms from the rear of the carriage, past a printing station, means operative during the return stroke of the carriage to cause advance of said continuous forms by said mechanism, a supply magazine at the rear of and below the carriage, from which said continuous forms are drawn and supplied, means to support said magazine swingably in the direction of carriage movement about an axis that is below the carriage and stationary with reference to the machine frame, and means comprising a motion-transmitting connection between said carriage and said supply magazine, above the said axis, to cause said magazine to swing concomitantly as the carriage is returned and the continuous forms are advanced and drawn upwardly from the magazine.

2. In a machine of the class described, a continuous form feeding apparatus comprising a carriage movable in one direction on a working stroke and in an opposite direction on a return stroke, a platen, a feed roll, mechanism for line spacing the platen and feed roll together as an incident to machine operations during the working stroke, and means automatically operable during the return stroke for augmenting the line space rotation of the feed roll, independently of the platen, an amount sufficient to present the

first line of a succeeding form in printing alignment with the platen irrespective of the number of line spaces used on the preceding form.

3. In a machine of the class described, a bed, a traveling carriage reciprocably movable along the bed in working and return strokes, a platen mounted on the carriage, a continuous form feeding roll rotatably mounted on the carriage, line space mechanism operable as an incident to operation of the machine during a working stroke of the carriage for imparting line space rotation to the feed roll, an element fixed on the feed roll for line space advancement therewith, and means for advancing the feed roll to bring the first line of the succeeding form into printing alignment with the platen, said means including a clutch having a driven element, a means for imparting rotation to said driven element during the return stroke of the carriage, and a pin fixed on the driven element and cooperating with the fixed element on the feed roll to rotate the latter.

4. In a machine of the class described, a traveling paper carriage, mechanism for moving the carriage through working and return strokes, a line space mechanism and a sweep feed means on the carriage for feeding continuous strip forms step by step and from any position on one form to a predetermined position on the next form, the sweep feed means acting to feed the forms when it is operated from a normal to an advanced position, means for coupling the sweep feed means to a stationary part of the machine, whereby return movement of the carriage will operate the sweep feed means, means for uncoupling the sweep feed means from the stationary part of the machine as soon as the forms have been fed to said predetermined position, and means for returning the sweep feed means to its normal position preparatory to the next feeding operation.

40

5. In a machine of the class described, a traveling paper carriage, mechanism for moving the carriage through its working and return strokes, a line space mechanism and a sweep feed means on the carriage for feeding continuous strip forms step by step and from any position on one form to a predetermined position on the next form, said sweep feed means acting to feed the forms when it is operated from a normal to an advanced position, means for coupling the sweep feed means to a stationary part of the machine when the carriage completes its working stroke, whereby return movement of the carriage will operate the sweep feed means, an element on the carriage, variably positionable means operated by said element on the carriage for uncoupling the sweep feed means from the stationary part of the machine as soon as the forms have been fed to said predetermined position, and means for returning the sweep feed means to its normal position preparatory to the next feeding operation.

ARTHUR LEON BOOTEN.
